MOTOR VEHICLE

Hermann H. F. Ahrens, Sindelfingen, Wurttemberg, Germany, assignor to Daimler-Benz Aktiengesellschaft, Stuttgart-Unterturkheim, Germany

Filed June 7, 1955, Ser. No. 36,394

Term of patent 7 years

(Cl. D14—3)

Des. 190,413

PAGE 2

FIG. 2

I claim:

The ornamental design for a motor vehicle, substantially as shown.
